UNITED STATES PATENT OFFICE.

CHARLES H. TUCKWOOD, OF JANESVILLE, WISCONSIN.

DEVICE FOR CONVERTING MOTION.

SPECIFICATION forming part of Letters Patent No. 323,546, dated August 4, 1885.

Application filed December 27, 1884. (No model.)

To all whom it may concern:

Be it known that I, CHARLES H. TUCKWOOD, of Janesville, in the county of Rock and State of Wisconsin, have invented certain new and useful Improvements in Devices for Converting Motion; and I do hereby declare the following to be a full, clear, and exact description of the invention, such as will enable others skilled in the art to which it appertains to make and use the same.

My invention relates to an improvement in devices for converting motion, the object of the same being to provide a simple, efficient, and durable device for converting reciprocating into rotary motion, which shall be particularly adapted to use with wind-wheels; and with these ends in view my invention consists in a pair of spring-actuated grips adapted to be forced into contact with the opposite faces of an annular groove by means of a reciprocating slide suitably connected therewith.

My invention further consists in certain features of construction and combinations of parts, as will be hereinafter described, and pointed out in the claims.

In the accompanying drawings, Figure 1 is a view of the device in front elevation with slide in elevated adjustment; Fig. 2, the same with slide depressed; Fig. 3, a front view of the grooved wheel with grips in position; Fig. 4, a plan view; and Figs. 5, 6, and 7, detached views of the grip, grip-operating lever, and one of the concentric arms, respectively.

A indicates a main shaft journaled horizontally in suitable bearings, *a a'*, at the front and rear, respectively. The bearings *a* are formed in standards or brackets B, rigidly secured to a suitable base, C, which may consist of a platform made for the particular purpose, or may be a floor or frame of a building adapted to the purpose. The standard B conveniently projects above the bearing *a*, and forms a support for the slide D, which is supposed to be reciprocated by the crank-rod of a wind-wheel or other power which it may be found desirable to employ. The slide D is secured in a suitable groove, *d*, formed on the upper end of the standard, and is provided with perforated lugs *d'* on its opposite sides for the attachment of the upper ends of the connecting-rod E. The front end of the shaft A is provided with a wheel, F, rigidly secured there-

on, preferably located immediately in front of the standard B. The face of the wheel F is provided with an annular groove, *f*. Two grips, G, each consisting of two half-sections, are adapted to fit within the groove *f* and have an easy-sliding motion therein, their outer and inner faces being shaped to conform to the corresponding faces of the groove. The grips are each provided with a rectangular slot, *g*, a part of the slot being formed in each half-section. The grips are also provided, one on its upper end and one on its lower end, with a shallow socket, *g'*, centrally located in the end for the purpose which will hereinafter appear. Two levers, H, are each provided with a laterally-extending rectangular-shaped lug, *h*, at its inner end, which lug is adapted to fit within the slot *g* in the grip. The said levers are slightly curved near their inner ends, and from thence extend outwardly to or beyond the outer ends of a pair of concentric arms, K. The arms K are loosely mounted on the forward end of the shaft A, and are provided at their outer ends with depending projections *k*, to the ends of which the above-described levers H are pivotally secured. The arms K are further provided with the bent auxiliary arms L, located near their pivotal support and extending laterally thereto, one upwardly and the other downwardly. The ends of the auxiliary arms L extend into the groove *f* a short distance above and below their respective grips, and said ends are provided with curved bars or rods *l*, rigidly secured thereto, the free ends of which engage the before-mentioned shallow sockets *g'* in the ends of the grips G. The curved bars or rods *l* are surrounded by coiled springs the tension of which is exerted against the ends of the grips, tending to force them off the ends of the curved bars *l*. The arms K are each further provided with a series of perforations, M, through which the lower ends of the connecting-rods E are pivotally secured thereto in the desired lateral adjustment, for regulating the stroke and changing the speed.

The operation of the device is as follows: Commencing with the slide D in elevated adjustment and considering the part of the device opposite the right hand of the person facing the front elevation thereof as the right of the device, and the opposite side as the

left, and suppose the slide D to start on its downward movement, the downward pressure on the end of the right-hand lever H is opposed to the pressure of the spring on the 5 right-hand curved bar l, and the motion of the outer end of the said right-hand lever H thereby anticipates the motion of the inner end of said lever, and hence of the grip G attached thereto, whereby the rectangular-shaped lug h in engagement within the slot in said grip is slightly rotated, causing the half-sections of said grip to separate and bind against the faces of the groove f. The 10 said right-hand grip is thus locked to the wheel F and causes it to rotate therewith. At the same time the downward pressure on the end of the left-hand lever H is in the same direction with the pressure of the spring on the 15 curved bar l in engagement with the left-hand grip, and, as the auxiliary arm L rotates with the arm K, the tension of the spring is held constantly against the said grip; hence the downward motion of the outer end of the left-hand lever H does not anticipate the downward motion of the inner end thereof, the 20 rectangular shaped lug h is not rotated, the half-sections of the grip are not separated, and the grip slides freely downward in the groove f. When the slide D makes its upward stroke, the conditions of the two grips 25 are reversed and the action is the same in principle as that just described. The left-hand grip is locked to the wheel F and right-hand grip released, and the wheel continues 30 its rotation in the same direction. The motion of the shaft A may be transmitted to a counter-shaft, A', through suitable multiplying-gears, O o.

It is evident that slight changes may be 35 made in the form and arrangement of the several parts described without departing from the spirit and scope of my invention—as, for example, other forms of spring than the coiled form shown might be used in connection with the auxiliary arms and grips, or the annular groove might be formed in the face of wheel F and grip caused to take laterally against its sides; hence I do not wish to be understood as limiting myself strictly to the construction 40 herein set forth; but,

Having fully described my invention, what I claim as new, and desire to secure by Letters Patent, is—

1. The combination, with a grooved wheel

55 suitably mounted, of a pair of two-part grips and means for operating the grips independent of each other, whereby they are alternately caused to bind against the opposite sides of the groove, substantially as set forth.

2. The combination, with a grooved wheel 60 suitably mounted, of a pair of sectional or two-part grips adapted to fit within the groove and means for alternately separating the grip-sections and allowing them to collapse, substantially as set forth. 65

3. The combination, with a reciprocating slide and a wheel provided with an annular groove, of spring-actuated two-part grips 70 adapted to fit within the groove, and independent devices connecting the slide and grips, whereby the latter are caused to alternately engage and release the sides of the groove, substantially as set forth.

4. The combination, with a reciprocating slide and a wheel provided with an annular 75 groove, of a pair of spring-actuated grips, each grip made of two parts and adapted to fit within the groove, and a pair of grip-operating levers actuated by the slide and adapted to act in conjunction with the springs in 80 causing the grips to alternately engage and release the sides of the groove, substantially as set forth.

5. The combination, with a reciprocating slide, a grooved wheel suitably mounted, and 85 a pair of grips adapted to fit within the groove of the said wheel, of a pair of grip-operating levers, a pair of concentric arms attached to said grip-operating levers and the slide, and a pair of auxiliary arms adapted to support 90 springs in contact with the grip, substantially as set forth.

6. The combination, with a reciprocating slide and a wheel provided with an annular groove, of a pair of two-part grips adapted to 95 fit within said groove, a pair of concentric arms adapted to be connected with the slide in different lateral adjustments, and devices connecting the said arms and grips, substantially as set forth. 100

In testimony whereof I have signed this specification in the presence of two subscribing witnesses.

CHARLES H. TUCKWOOD.
